CLAIM

The ornamental design for an electrical connector, as shown and described.

DESCRIPTION

FIG. 1 is a front perspective view of an electrical connector showing our new design, viewed from above and to the right;

FIG. 2 is another front perspective view thereof, viewed from below and to the left;

FIG. 3 is a rear perspective view thereof, viewed from above and to the left;

FIG. 4 is another rear perspective view thereof, viewed from below and to the right;

FIG. 5 is a top plan view thereof;

FIG. 6 is a bottom plan view thereof;

FIG. 7 is a right side elevation thereof;

FIG. 8 is a left side elevation thereof;

FIG. 9 is a front end elevation thereof;

FIG. 10 is a rear end elevation thereof;

FIG. 11 is a front perspective view of another electrical connector showing our new design, viewed from above and to the right;

FIG. 12 is another front perspective view thereof, viewed from below and to the left;

FIG. 13 is a rear perspective view thereof, viewed from above and to the left;

FIG. 14 is another rear perspective view thereof, viewed from below and to the right;

FIG. 15 is a top plan view thereof;

FIG. 16 is a bottom plan view thereof;

FIG. 17 is a right side elevation thereof;

FIG. 18 is a left side elevation thereof;

FIG. 19 is a front end elevation thereof; and,

FIG. 20 is a rear end elevation thereof.

(Continued)

In the drawings, the broken lines depict unclaimed portions of the electrical connector that form no part of the claimed design.
